MEANS FOR REGULATING EXPLOSION-ENGINES DRIVING BLAST AND LIKE APPARATUS.

No. 824,743.

Specification of Letters Patent.

Patented July 3, 1906.

Application filed April 28, 1903. Serial No. 164,713.

To all whom it may concern:

Be it known that I, HANS RICHTER, engineer, a subject of the German Emperor, residing in Nuremberg, in the Empire of Germany, (whose full postal address is 15 Gleisbühlstrasse, Nuremberg,) have invented certain new and useful Improvements in Means for Regulating Explosion-Engines Driving Blast and Like Apparatus, of which the following is a specification.

The use of gas-engines for driving blowing or blast apparatus has hitherto had severe drawbacks, as it was necessary to run them at almost their highest power in order to work economically, while pressures considerably above the normal are from time to time required in the blast—for instance, in the case of choking of the furnace. These two opposing conditions are allowed for by the present invention in that the blowing-machine itself is employed in order to strengthen the action of the gas-engine when a larger quantity of air is to be supplied or a higher pressure to be produced by the said blowing-engine. In this case the supply of air to the gas-motor is closed to the outside air and instead thereof connected with an air-pipe branched off one of the blast-cylinders or the blast-pipe, while a suitable device for increasing the gas-pressure, such as a fan inserted in the gas-pipe, is set in operation, so that both air under pressure and gas under pressure are at disposal for feeding the gas-engine. The regulator of the gas-motor is further so adjusted that the residues of combustion remaining after each expulsion-stroke are entirely driven out by the entering air under pressure, the introduced mixture consisting thus exclusively of combustible gases and of atmospheric air, while there are no residues of combustion from the preceding explosion contained therein or at least no considerable quantities of such residues. Consequently there is increased not only the initial pressure of the explosive mixture, but also the quantity of explosive parts which it contains.

The operating gas-engine, the cylinder *a* of which is provided with an air-inlet valve *b*, gas-inlet valve and exhaust-valve *d*, acts, by means of a crank-shaft *e*, on a blast-cylinder *f*, on the covers of which inlet and outlet

valves *g* and *h*, respectively, may be distributed, for instance, in semicircles. The compressed air passes through the valve *h*, first into a collecting-chamber *i* and from there into the blast-pipe *k*. From the latter a branch pipe *l* is carried to the air-admission valve *b* of the gas-engine, said branch pipe *l* being adapted to be connected, by means of a shut-off valve or the like *m*, either with the outer air or, as shown in the drawings, with the blast-pipe *k*. The gas-supply pipe *n* is also forked into two parts *o* *p*, in one of which, *o*, a fan *q* is inserted. The pipe *n* may be placed in communication with each of these parts *o* or *p*, as the case may be, by means of valve *r* and also closed against the other one, *p* or *o*, as the case may be. Both parts *o* and *p* connect behind the fan with a common gas-pipe *s*, which ends at the gas-inlet valve *c*.

In regular working the branch pipe *l* is in communication with the outer air, while the fan *q* is shut off from the gas-inlet pipe. The gas-engine consequently receives both air on the course *m l b* and also gas on the course *n r p s* at atmospheric pressure, and therefore works economically if it is of such dimensions that it gives an effective delivery at about the normally required pressure of air corresponding approximately to the full atmospheric initial pressure of the mixture. If, however, a larger quantity of air is to be delivered by the blowing-engine or a higher excess pressure produced, the air-pipe *l*, leading to the gas-engine, is closed by closing the valve *m* to the outer air, and at the same time it is brought in communication with the blast-pipe *k*, containing compressed air. The valve *r* must also be so turned that now the gas passing out of the pipe *n* centrically into the fan *q* (operated by means of an electro-motor or other suitable machine) is brought by the latter to a higher pressure and conveyed to the pipe *s* and the gas-inlet valve *c*. The valves *r* and *m* are influenced, with the aid of a system of lever-rods *t* *t'* *t''* *t'''* *t''''* from a centrifugal governor *u*, which is turned by a worm and wheel *v w*, provided on the crank-shaft *e* in such a manner that said valves occupy during normal work the positions *m' r'* indicated. They are adjusted by means of the governor-sleeve *x*,

which is shifted to the left as soon as the centrifugal balls u drop, so that they occupy the position $m\ r$ drawn in full lines.

The distribution-gear of the gas-engine 5 being suitably arranged and adjusted, the result of the combination described is that the method of working called for in the opening paragraphs of this specification is obtained.

10 I declare that what I claim is—

In an apparatus for increasing the power of explosion-engines which drive blast-engines, the combination of a blast-pipe connected to the blast-engine, a cylinder, a piston therein, a connection from the cylinder to a gas-supply, a connection from the cylinder to the blast-pipe, an opening to the blast-pipe connection from the atmosphere and con-

trolling means whereby either compressed air or air at atmospheric pressure may be supplied to the cylinder, and means in said gas connection for supplying gas at either atmospheric or increased pressure, said means consisting of a gas-forcing device in one part of the connection and a valve for allowing 25 the gas to flow directly to the cylinder when air at atmospheric pressure is required or for directing the gas to the gas-forcing means when an increased pressure is required.

In witness whereof I have hereunto set my 30 hand in presence of two witnesses.

HANS RICHTER.
